(57) **CLAIM**

The ornamental design for a live front switchgear voltage sensor, as shown and described.

DESCRIPTION

FIG. 1 is a perspective view of the live front switchgear voltage sensor;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the drawings are for the purpose of illustrating portions of the live front switchgear voltage sensor that form no part of the claimed design.
